Letters Patent

The Schedule referred to in these Letters Patent and making part of the same containing a description in the words of the said John Straight, himself, of his improvement, in the loom for weaving carpets and other figured cloths.

To all to whom these presents may come
Be it known that of John Straight of Haddonfield in the County of Bergen and State of New Jersey have invented a new and useful improvement in the Looms for weaving carpets and other figured cloths, by which he is enabled to apply water or other power, in their operation, and that the following is a full & exact description of the construction and operation of the said machine, as invented or improved by me. Note; In the following description that end of the loom on which is the driving pulley will be called the pulley end and the opposite the gear end, that side of the loom on which the yarn beam containing the yarn or web will be called the back side and the opposite the front side, and further that as this improvement does not at all alter the engine for forming the figure, except that the cam on the engine shaft works the uprights which has precisely the same effect upon the engine with the operator's foot when worked by men, no description of said engine is given, as it is well known and is not altered or affected by this improvement. This machine consists of a frame four feet and two inches deep and three feet and ten inches long and three feet and three inches high and is represented on the plate by the letter A and is formed by two ends of iron or wood, the posts of which are connected by two girders, the lower one foot upwards from the floor, and the upper twenty three inches from the lower, these ends are connected and held together by beams on each end, the lower beam is placed with the top surface even with the

D. M. ALLEN

under side of the lower girth, and the upper beams even with the top of the posts. A slotted bearing is cast on the outer edge of the back posts twenty two inches from the foot of the posts to sustain the main beam, which is held in by pins and kept back by the ordinary friction strap and lever. From the bottom of each front post a stand is projected backwards, six inches and bolted through a slit in the posts just above the feet to sustain the rod or shaft on which the sword of the lathe plays marked a. Two posts are then raised from the frame to support the engine in the usual way and bolted to each girth of the frame marked B. Two stands are bolted to the under side of the upper girth fifteen inches inward from the backside to sustain the bearings of the main shaft, which is marked C and rests upon the caps of the bearings.

From the top of the lower girth twenty, inches from the front side are raised two stands to sustain and form the bearings of the picker shaft marked D. and fourteen inches back of the lat shaft. on the same girth are raised two stands ^{to sustain} and form the bearings of the engine shaft marked B and directly over the picker shaft two stands are raised from the upper girth to sustain and form the bearings of the crank shaft marked E. The driving shaft is then entered in its bearings having on the pulley end and outside of the frame a post and loose pulley of seven inches diameter and two and a half inches on the face and on the gear end a pinion of 13 teeth. The picker shaft is then placed in its bearings having near its gear end a cog wheel of 96 teeth gearing into the pinion on the main shaft or driving shaft and just within the frame on each side a pulley or blank wheel of thirteen inches diameter and two and a half in the face. These pulleys have each two staples or drivers projecting outward one and a half inch and two & a half inches long on opposite sides of the pulleys and placed near opposite ends of the pulley to come in contact with the troughs on the picker beams hereafter described. The crank shaft marked E is then cut out

on its bearings having on its gear end a cog-wheel of 24 teeth gearing into it to the cog-wheel on the picker shaft; and on each end a crank of $4\frac{1}{2}$ inches radii, or 9 inches sweeps furnished with a stud and friction pulley of 1½ inch diameter. The engine shaft marked B is then placed in its bearings having on the gear end a cog-wheel of 48 teeth gearing into wheel on the picker shaft and just within its bearings. On each side of the frame a crank-stud slit in the ends to form a guide for an oval cam, within which it plays on a pin or friction pulley so placed as to form a crank of 3 inches radii, and giving the cam a motion up and down of 6 inches and serve to shift the shuttle boxes as hereafter described. Four and a half inches, inwards from these cranks on each side is another crank stud of 5 inches radii and furnished with a stud and friction roller, projecting outwards to raise the section of a cam, connected with the uprights ^{of the purpose} which govern the engine and serve the purpose of the treadles in the common loom. The foregoing form the principle moving parts of the loom, and the gearing mentioned has five teeth to each inch of the diameter of the wheels and the picker shaft is marked D. A lathe is formed by entering two swords of cast iron on this rod or shaft within the ends of the frame and connecting them on the top by a cross bar of wood, so that the race board on it will be therefore of an inch lower than the breast beam when brought up. These swords have a hole to receive the rod at the bottom and are slotted to receive a stud to work the lathe up lower. Two and a half inches above the upper guides they receive the stands of the cam, which give them motion from the crank and are firmly bolted to them. This stand is of one piece of casting with the cam, which is a semicircular slit corresponding to the radii of the crank and the diameter of its friction roller and is marked C, and the lathe with which it is connected is marked D; above these stands the swords are slotted ^{upwards} to receive the shiftings and levers for mounting.

mentioned the slay or reed frame is then placed on the back side of the frame bar of the lathe, with its end pieces projecting upwards eight inches to receive the top piece which is mortised for them and the slay is received and held firm by grooves in the bottom and top pieces in the usual way of power looms, and the upper ends of the swords are cast with flanges to receive the right bar and the bottom piece of the slay frame through which they are firmly bolted at each end. This formed this part constitutes the moving lathe, having an irregular but uniform motion carrying the slay to and from the work.

Two swords are then placed upon the part of the lathe and just out side of the frame and rise to the same height with the swords before mentioned and serve to sustain the shuttle boxes at each end of the lathe. Six inches up from the rod, these swords is a socket guide and nineteen inches above this it receives another for the rod which turns the shuttle wheel hereafter mentioned, and six inches below the last mentioned socket the sword receives a stud for a knee which shifts the rods if the rod before mentioned to and from each side of the wheel which it moves together with this stud and between it and the sword a small stand is raised and projected forwards and outwards to sustain the bottom of a spiral spring and receive a friction wire inches above this another stand is projected upwards and forwards from the sword to hold the upper guide of the rod through which it passes and is formed into a steady beam now fitting the sides of the shuttle wheel, a spiral spring is placed between the guides and the rod is passed down through the guides and the spring and is held by a pin through the rod resting upon the top of the spring so that the power of the spring is employed to keep the shuttle box in place when it has been moved as aforesaid. above this last mentioned stand the

279

wood divided. the front part projects forwards one inch and upwards seven inches. the back part projects backwards five inches and rises even with the front. and they receive upon the top on each side of the loom, a double shuttle box six inches wide and twenty five inches long having a dividing board in each in the middle, and accommodates two shuttles. A small sword is then entered on the ends of the sword rods, six inches outwards from the last and rise parallel to them the front and are secured to them by two bolts passing through slits between the swords, the lower one seven inches from the rods, the other one inch from the top. a brace is then bolted to an ear on the under side and outer end of each shuttle box and to the last mentioned sword just below the upper bolt, and thus forms a firm support for the outer ends of the shuttle boxes which are connected by a firm piece of wood passing back of the slay and cut away on the front side to give room for the front shuttle box to be brought in a line with the slay which piece of wood is bolted firmly to the back shuttle box on each side the part of the sword before mentioned projecting backwards is slotted one and a half inch below the division perpendicular and the projecting part is also slotted perpendicular near the top one and a half inch. and the lower part of the top slit, and the upper part of the lower slit, are united by an angular slit all which slits are $\frac{1}{4}$ of an inch wide and so formed that a rod passing from top to bottom, will move the sword backwards two and three quarters inches and the rod will move forward four inches. The back division of the shuttle box on the gear end and both divisions of the shuttle box on the pulley end, are in form like the common shuttle box if you turn it round in the bottom to guide the picker and furnished with friction springs to hold the shuttle and picker from rebounding when they arrive in these places. But as many different coloured yarns must be woven into each

plots, and other figured goods, and as one shuttle will be required for each colour, the following apparatus is affixed to receive these shuttles and change them as the figure requires. A circular stand is bolted to the sword holding the shuttle box with the same bolt and projects forwards 3 inches and upwards one inch and a quarter. And from the under side of the shuttle box and twenty inches from the stand, a similar stand is projected to hold the shafts of an equilateral polygon marked K, and having as many sides, as the number of shuttles desired (say) nine as represented on the plate which will bring every side when brought square with the bottom of the shuttle box in a line with the outside piece which with the bottom of the box is removed or left vacant the whole length of the polygon and its sides now form the side of the box. Upon each of the vertices or points of the polygon, an angular piece is secured in such a manner as to form right angles with the sides, so that when the sides form the front side of the box the angular pieces will form the bottom, which must have a lip turned upwards $\frac{3}{8}$ of an inch and $\frac{1}{4}$ of an inch wide to hold in the bunch wheel of the shuttles, and prevent its falling out when turned downwards with the polygon. A small spring is also fixed on the outside of the angular pieces and projecting a little over the space to be occupied by the shuttle to hold the other side of it. These angular pieces may be cut or scribed on the outside to make them light and tasteful, and there must be a space left between them and the dividing board of the shuttle box which forms the backside of the front box, a space to form a groove for the picker which is kept in by a clasp which slides in a plough on the under side of the box just under the dividing board. Upon the end of the polygon near the front a pulley is made fast having a flange on the outside of $\frac{3}{8}$ of an inch, leaving a flange or some $\frac{3}{4}$ of an inch deep between the flange and the end of the pulley.

gon. some pins or turnels $\frac{1}{4}$ of an inch in diameter are then passed through the flange into the polygon, in a circle, and at equal spaces, and in a line with the pieces forming the bottom of the shuttle bay, when the shuttle is in action. The rod, which turns this polygon, is then inserted in its socket near the lower part of the sword, where it is round, and into the upper socket where it is flat. And has room to move sideways to an inch. Above this it is forked and comes up on each side of the pulley last mentioned, having a catch projecting inwards from each fork in such a manner that when the front catch is held off from the pulley, the back catch will be free, or pass its pin without a contact, and (vice versa) it stands in then bottom to the sides of the lower guide on the gear end fifteen inches from the front of the frame, and by tapers downwards 3 $\frac{1}{2}$ inches where it takes a stud projecting outwards and forms the fulcrum of a lever marked L. This lever extends backwards of the fulcrum fifteen inches and forward of it five inches when a piece of iron is bolted to it, and forward until it comes by the side of the lower end of the rod above mentioned where it is connected with it by a piece of iron bolted to each. It stands in then bolted to the upright piece which works the engine, on the gear side nine inches above the upper guide, projecting backwards two inches and outwards two inches through this stand a rod is projected downwards and made fast with screws with the lower end directly over the back end of the lever last mentioned, so that when the upright descends, this rod will strike the end of the lever and carrying it down with it, consequently, takes the other end and carrying with it the rod before mentioned which by the catch of the fork which is in gear will cause the pulley to move just one ninth part of a revolution and bring a new shuttle in place. The catch on the front side of the fork of the rod will always tend to be in action with the pins

kind of the pulley by the gravity of the rod, to overcome this and bring the catch on the back fork in action. A knee is put upon the stud before mentioned for it, on the sword which will bring the stud on the short part of the knee, against the back part of the rod and the long part of the knee will extend forwards of the rod and must be raised to overcome the gravity of the rod by bring the catch on the back fork into contact with the pins of the pulley which will reverse the motion of the polygon and turn it forwards, and bring up or back the shuttles which have passed. But when the shuttles have all been used and returned this knee must be raised to commence another which is effected by attaching a string to the needle, which changes the averse of the engine for a new figure passing it over a small pulley and attaching it to the long part of the knee by which it will be raised, and the catch on the front fork will again turn the polygon and the shuttles will be brought back again in rotation, but as some of the colours will want to pass several times, to form the figure without changing it will be necessary to make a number of shots with the shuttle containing it before the polygon moves to change it, to effect this a small stand is bolted to the lower girth of the frame, twenty one inches from the back part and projected downwards nine inches having a stud at the lower end which receives a knee extending inwards (fifteen inches) and upwards five inches. - the outward part comes up close by the outside of the lower wheel under the further end, just forward where the rod from the upright strikes it, and has a catch or catch formed on the upper end projecting inwards, so that when the knee descends, it will draw out the upper part of the knee by the action of the catch until the knee is down when the catch will be thrown over the top of the knee by the weight of the long end of the knee, and the knee will be held down, and the polygon will remain stationary.

and the shuttle in the box will be worked until this latches or catch is drawn off, which is effected by attaching a string to the shifting needle of the engine and the inside end of this fence, which raises that end, and sets the lever free at every change in the figure ready to be acted upon by the next movement of the upright and being in a new position as before described. Having thus described the manner of shifting the shuttle. I shall next describe the manner of propelling them through the piece from side to side of the lattice.

For this purpose a stand is projected downwards from each of the lower girths, eight inches on the inside and an four-tear inches back from the front post to these stands at the bottom, a cross piece is bolted connecting them together. In the center of this piece, a stand is raised 5 inches from which is projected forwards a stand for 2 vibrating pulleys to each of which are firmly bolted the picker rods, extending upwards eighteen inches, at the top of which is affixed the picker strings connected in the usual way with the pickers in the shuttle box as to each of these pulleys on the top a strap of leather is bolted which passing through the shank on the end of the picker lower comes back and buckles near the top of the pulleys. These picker levers are nineteen inches long and are sustained by studs in the cross piece half mentioned eleven inches from the pulley which form their fulcrum and have each a staple in their outer ends to receive the connecting rod which moves them. Two studs are then bolted to the upper girths seventeen inches from the back post projecting upwards four inches on each side of the frame. Two levers are put upon these studs and pass forward directly over and resting upon the pulleys or blank wheels on the picker shaft and extending forwards until they come directly over the staples in the picker levers where they receive each a regulating screw with an eye in the same.

lower end to receive the connecting rods, which are formed with a hook on each end, which is entered in the staple and eye of the lever to connect them together. The levers are mortised where they rest on the blank wheels and a scored track is fitted in them against which the staples on the blank wheel come in contact, by which they are suddenly raised, bringing up with them the outer ends of the picker levers and consequently turning the vibrating pulley towards the operating pulley, bringing with it the picker rod and the string connecting the upper end of the rod with the picker, by which the picker will be suddenly brought against the shuttle with an impetus that will propel it to the opposite boy, and it will be returned in its time by the action of the staple on the blank wheel on its catch lever and the shuttle in both apartments of the bays will be worked in this manner in rotation, and the front and back shuttle bays will require to be shifted to a proper position with the slay, at each stroke of the latter. To effect this a change rod is passed through the angular slit in the sword sustaining the shuttle bays and through the upright slits in the swords having a uniform motion, and sustaining the latter, and when it is in the perpendicular part of the angular slit at the top of the sword, the back board of the back shuttle bay will be in a line with the front of the slay and the back shuttle containing the ground colour will be in a situation to pass the piece but the other bay must be moved into its place for the next stroke to make the figure. To effect this change the eye of a rod is passed round this change rod just within the inside swords, and extends downwards twenty six inches where it enters a slot in the end of a lever and is held to it by a pin passing through each part of the lever and the rod which is here made flater. This lever extends backwards fourteen inches, where it receives a pin in a slot on the inside of the lever which serves as its fulcrum, it

is continued back until it comes directly under the engine shaft where it receives upon ^{it} the stem of the oval cam marked M- on which the crank stand first described, on this shaft plays, upon this cam a slotted stand is projected upwards with its forks passing each side of the engine shaft to prevent any lateral motion, and the crank will give the cam and the lever an upright and descending motion as it passes its sides carrying with it the lever and cause the rod on the other end to rise and fall four inches forcing the change rods which it clasps to rise and fall with it in the slots in the sword following the lathe and as it descends it will enter the angular slit in the sword holding the shuttle boxes and cause it to move backwards two and three quarter inches and bring the back board of the front shuttle box in a line with the front of the slay, when the shuttle in that box will be ready to pass, and this change will take place uniformly at every shot of the shuttle, but as the shuttle may by accident fail to reach its place in the opposite box after receiving its stroke, it becomes necessary, in that case to prevent the lathe from coming forward and injuring the web. For this purpose a stand is bolted to the lower girth on the pulley side sixteen inches back from the front post projecting outwards seven inches, a stud raised upwards from this stand serves as a fulcrum to a lever to shift the driving belt from the fast to the loose pulley. The back end of this lever is formed into a fork which straddles the belt and moves it off and on. The front end of this lever comes forward to the front of the frame where it is connected with an upright lever having its fulcrum in a slotted stud placed about nine inches up the front post, and is continued upwards to the top of the post, where it is formed into a handle, and in a line with the under side of the breast beam, and secured by a staple and pin the gear end of the front post.

rod is held by two clasps to the breast beam. the clasp on the gear end forms a shoulder for a spiral spring as well as for a guide to the rod which spring covers the rod sixteen inches and is kept together by another clasp held to the rod by a set screw so that the expansion of the spring will always tend to drive the rod endwise towards the pulley side of the frame. The front side of this rod has a score in the middle to receive a catch to hold it against the spring when the loom is in action. This catch is sustained in two stands from the under side of the breast beam and is held up to the rod by a spiral spring in the same manner as the protection rod and is continued backwards through the stands seven inches and a half in form of a rod and is received in a hole in a stand on the middle of the lathe when it comes up to press on the waist. on the lower end of this stand is a stand projected forwards sustaining two flat pieces of iron so heavy at the lower ends, as always to keep them upright, when not acted upon and so placed as to shade or cover the hole in the stand. to the lower end of these pieces or stoppers on each side strings are fixed and connected with the picker strings in such a manner that when the shuttle has reached its place in the box, the piece of iron will be drawn with it and the hole in the stand will be unmarked and the rod will return and the lathe will come forward, but should the shuttle stop short, the stopper will cover the hole stop the rod and compress the spring forcing the rod back will set free the catch and the spiral spring will force the protection rod towards the pulley side of the frame, and by the action of the lever instead of removing the driving belt from the fast to the loose pulley and the loom will be stopped, which may be put in motion again by pulling up the handle of the upright lever until the catch seizes the protection rod and unless the

score. To work the engine a stand is bolted on each of the upright pieces which move the engine. Marked N. eight inches above the upper girth and turned inwards three inches and downwards fourteen inches when it is formed into the section of a circle with the ends extended in a line with its chord. and rests upon the hub of the crank shaft before described as inside on the engine shaft with its centre downward and having the same radii with the crank which are placed on opposite sides of the shaft so that when one upright is raised the other will remain quiet and these cams or sections of circles must be so formed that the one upright will rise and consequently down and give sufficient time for the needles of the engine to recover before the other rises. These crosses uprights will be moved alternately by the cranks, and a slatted stand is bolted to the cam. sticking the shaft to prevent any lateral motion ^{and direction} of these uprights is all that works the engine and serves all the purposes of the man's foot upon the treadles. when working the common engine soon. Having now described the manner of making the cranks it remains to describe the method of taking it away as it is made, for which purpose the common ratchet wheel and pinion with steel lever and pins marked by the studs for this before mentioned on the sword of the rattle in the usual way, but instead of placing the cog wheel which goes into the pinion of the ratchet wheel on a cloth beam, I place on the middle of three rollers of any desirable diameter (say 24 inches on the pulley) one. I place these rollers in a line one above the other in front of the breast beam, having the surface of the upper roller a little higher than the top of that beam and fasten three rollers at the top end with each passing over wheels. Then pass the cloth over the top roller and back to the lower it and the middle roller then forward between the uprights.

middle and lower roller and it will be taken away by the friction of the cloth and rollers and the draw will be uniform and I avoid all the difficulties of an increasing beam, & this improvement does not at all alter the engine for forming the figure or

any of its movements except that the cams on the uprights and crank on the shaft give the motion to the uprights, but as this motion is precisely the same and has the same effect upon the engine as the operators foot when worked by man, no description of said engine is given, which serves to raise the shade and form the figure, and to the invention or improvement of which I lay no claim, and the above description is for a loom where the ground colour of the carpet is one, and the shuttle containing it is thrown alternately with the shuttle in the front box containing the colours for the figure, but if any number of colours are wanted in the ground, a similar polygon with that described may be placed to the back side of the back shuttle box, on the pulley end of the lathe and any number of shuttles with different colours may in like manner be worked into the ground. Many parts of the machinery above mentioned have been known and used in power looms for plain cloth, such as the cam, and crank moving the lathe, the take up motion of the ratchet wheel and others to which I lay no claim whatever. But I do specifically, claim - at my invention the polygon for holding and changing the shuttle, the double shuttle boxes, and means of changing them to the slay, and the application of the cams to raise the uprights and work the engine, and the general arrangement and combination of machinery by which these several movements are effected.

In testimony that the foregoing is a true and exact description of my said improvement I have hereunto set my hand and seal this 11th day of April 1834.
